UNITED STATES PATENT OFFICE

2,449,398

ADJUSTABLE HEADS FOR PAPER WINDING REELS

Leo Leas, Vicksburg, Mich., assignor to Lee Paper Company, Vicksburg, Mich., a corporation of Michigan

Application February 13, 1946, Serial No. 647,298

6 Claims. (Cl. 242—124)

1

This invention relates to improvements in adjustable heads for paper winding reels.

The main objects of this invention are:

First, to provide a reel for reeling paper as it is discharged from paper making machines and for other uses where wide webs of paper are to be reeled, which is strong and durable in structure and one which may be readily adjusted to webs of different widths.

Second, to provide a structure having these advantages which may be very easily and accurately adjusted, and one in which the adjusted position is maintained.

Objects relating to details and economies of the invention will appear from the description to follow. The invention is defined and pointed out in the claims.

A structure which embodies the features of the invention is illustrated in the accompanying drawing in which:

Fig. 1 is a fragmentary perspective view of a winding reel embodying this invention.

Fig. 2 is an enlarged fragmentary view mainly in longitudinal section on line corresponding to line 2—2 of Fig. 3.

Fig. 3 is a transverse section on line 3—3 of Fig. 2.

In the embodiment of this invention illustrated, the main shaft 1 is supported in suitable bearings and driven at suitable speeds for the particular work.

The reel illustrated is provided with end heads 2 and an intermediate head 3 to which the reel spool bars 41 are fixedly secured by the screws 4, the heads being provided with a plurality of faces 5 so that the bars are more effectively supported when clamped thereto. The heads are axially spaced on the shaft and keyed thereto as indicated at 6. The reel flanges 7 are annular, having an internal diameter sufficient to loosely embrace the spool bars as is shown in the drawing.

These flanges are supported for axial adjustment by means of the axially adjustable sleeves 8, slidably supported on the shaft 1. These sleeves are provided with nuts 9 fixedly supported by the arms 10 projecting from the sleeve to receive the screw portion 11 of the adjusting shaft 12. This adjusting shaft is arranged through adjacent head members and is provided with abutment collars 13 to prevent axial movement of the shaft while permitting its rotative movement.

The flanges 7 are supported by angled brackets 14 disposed with their inner arms 15 radially and secured to the sides of the sleeve at 16. Outer longitudinal arms 17 are disposed longi-

2

tudinally between adjacent support bars and are secured to the outer sides of the reel flanges by the clips or plates 18.

5 The adjusting shaft 12 is provided with a sprocket 19 at its outer end, this sprocket being connected by the sprocket chain 20 to the sprocket 21 which constitutes a driving sprocket rotatably mounted on the shaft 1 and provided with a hand wheel 22 for convenience in adjustment. The driving sprocket 21 is secured in its adjusted position by means of the set screws 23.

It will be understood that in use the entire structure rotates as a unit. It will be understood that the second flange is supported and adjusted in the same manner as that shown in left-hand end of the figures and described.

The sprocket chain 20 is provided with an idler 24 carried by the spindle 25. For convenience in assembling the sleeve 8 is formed in sections having opposed ears 26 receiving the screws 27 whereby the sleeve sections are secured together. The outer arms of the angle brackets 14 are supported by the sleeve for longitudinal adjustment between the spool bars 41.

25 The structure is capable of handling heavy loads and has a very considerable variation in the matter of accommodating webs of different widths.

The flanges may be accurately adjusted with 30 edges of the web to insure uniform and accurate winding, and also to accommodate webs of widely varying width.

This improvement has been illustrated and described in an embodiment which is regarded as 35 highly practical. No attempt has been made to illustrate or describe other embodiments which are contemplated, as it is believed that this disclosure will enable those skilled in the art to embody or adapt the invention as may be desired.

Having thus described the invention, what is 40 claimed as new and desired to secure by Letters Patent is:

1. In a winding reel, the combination of a 45 shaft, end and intermediate reel head members axially spaced on said shaft and keyed thereto, spool bars secured to said head members in angularly spaced relation, annular flanges embracing said bars, and means for adjusting and supporting said flanges, each comprising a sleeve axially slidable on said shaft, angled supporting brackets having their inner arms disposed radially and secured to said sleeve, their outer arms being disposed longitudinally between certain of 50 the spool bars and secured at their outer ends to

the outer sides of the flange, a flange adjusting screw rotatively mounted in adjacent end and intermediate head members and projecting through the end member and provided with a driven sprocket on its projecting end, said screw being radially offset from said shaft, said sleeve being provided with a nut coacting with said screw, and a driving sprocket rotatable on said reel shaft at the outer side of the end member and having sprocket chain connection with the driven sprocket on said screw, said driving sprocket being provided with a hand wheel and with means for securing it to said reel shaft in its adjusted position.

2. In a winding reel, the combination of a shaft, end and intermediate reel head members axially spaced on said shaft and keyed thereto, spool bars secured to said head members in angularly spaced relation, annular flanges embracing said bars, and means for adjusting and supporting said flanges, each comprising sleeves axially slideable on said shaft, angled supporting brackets having their inner arms disposed radially and secured to said sleeve, their outer arms being disposed longitudinally between certain of the spool bars and secured at their outer ends to the outer sides of the flange, and an adjusting screw rotatively mounted in adjacent end and intermediate head members and radially offset from said shaft, said sleeve being provided with a nut coacting with said screw.

3. In a winding reel, the combination of a shaft, reel head members axially spaced on said shaft and keyed thereto, spool bars secured to said head members in angularly spaced relation, an annular flange embracing said bars, and means for adjusting and supporting said flange, comprising a sleeve axially slideable on said shaft, angled supporting brackets having their inner arms disposed radially and secured to said sleeves, their outer arms being disposed longitudinally between certain of the spool bars and secured at their outer ends to the flange, a flange adjusting screw rotatively mounted in said head members and projecting through one of them and provided with a driven sprocket on its projecting end, said screw being radially offset from said shaft, said sleeve being provided with a nut coacting with said screw and a driving sprocket rotatable on said reel shaft at the outer side of the head member, through which the screw projects, and

having sprocket chain connection with the driven sprocket on said screw, said driving sprocket being provided with a hand wheel and with means for securing it to said reel shaft in its adjusted position.

4. In a winding reel, the combination of a shaft, reel head members axially spaced on said shaft and keyed thereto, spool bars secured to said head members in angularly spaced relation,

10 an annular flange embracing said bars, and means for adjusting and supporting said flange, comprising a sleeve axially slideable on said shaft and internally supported thereby, angled supporting brackets having their inner arms disposed radially and secured to said sleeves, their outer arms being disposed longitudinally between certain of the spool bars and secured at their outer ends to the flange, and adjusting means for said sleeve.

15 20 In a winding reel, the combination of a shaft, reel head members and a reel spool element carried thereby, an annular flange embracing said spool element for axial adjustment relative thereto, a sleeve disposed on said shaft between said head members for axial adjustment,

25 flange supporting brackets carried by said sleeve, a flange adjusting shaft rotatably mounted on said head members and having a threaded portion, said sleeve being provided with a coacting nut element, and a driving gear for said shaft rotatable on said reel shaft for manual adjustment and having driving connection to said adjusting shaft.

30 35 6. In a winding reel, the combination of a shaft, reel head members and a reel spool element carried thereby, an annular flange embracing said spool element for adjustment axially thereof, a sleeve disposed on said shaft between said head members for axial adjustment, flange supporting brackets carried by said sleeve, and means for adjusting said sleeve from the outer side of one of said head members.
